(57) **CLAIM**

The ornamental design for a straw for a cup, as shown and described.

DESCRIPTION

FIG. 1 is a top, front perspective view of a straw for a cup showing our new design;

FIG. 2 is a front view thereof, the rear view being identical to the front view;

FIG. 3 is a right side view thereof, the left side view being identical to the right side view;

FIG. 4 is a top view thereof; and

FIG. 5 is a bottom view thereof.

FIG. 6 is a top, front perspective view of a straw for a cup showing our new design;

FIG. 7 is a front view thereof, the rear view being identical to the front view;

FIG. 8 is a right side view thereof, the left side view being identical to the right side view;

FIG. 9 is a top view thereof; and,

FIG. 10 is a bottom view thereof.

The features shown in broken lines depict environmental subject matter only and form no part of the claimed design. The bolded, short dash-long dash lines, as shown in FIGS. 6–10, indicate the boundary of the claimed design and form no part of the claimed design.
